UNITED STATES PATENT OFFICE.

JESSE THOMAS MERRITT, OF FAYETTEVILLE, TENNESSEE.

TUG-BUCKLE.

SPECIFICATION forming part of Letters Patent No. 391,545, dated October 23, 1888.

Application filed February 25, 1888. Serial No. 265,233. (No model.

To all whom it may concern:

Be it known that I, JESSE THOMAS MERRITT, a citizen of the United States, residing at Fayetteville, in the county of Lincoln and State of Tennessee, have invented a new and useful Improvement in Tug-Buckles, of which the following is a specification.

My invention relates to improvements in tug-buckles to connect the tug-strap to the trace; and it has for its object to provide a buckle from which the straps cannot become accidentally detached; furthermore, to provide a buckle which will enable the strap when engaged therein to lie flat.

15 With these objects in view the invention consists in a certain novel construction and arrangement of devices, which are fully set forth hereinafter, in connection with the accompanying drawings, wherein—

20 Figure 1 is a perspective view of the buckle with the tug-strap and trace attached thereto. Fig. 2 is a longitudinal central sectional view of the same. Fig. 3 is a similar view showing the manner of releasing the tug-strap. Fig. 4 is a perspective view of a catch or hook embodying my invention. Fig. 5 is a longitudinal central sectional view of the same.

25 Referring by letter to the drawings, A designates the tug-strap, having a series of perforations, *a a*, therein, and B designates a portion of the trace, to the front end of which is attached the curved loop C. This loop is provided with curved and slotted side arms, *c c*, the function of which will be hereinafter fully explained.

30 D designates a plate having the outwardly-extending ears E E at its front end and the lateral studs F F at its sides. A bolt or spindle, G, is arranged in apertures in the ears E.

35 H represents a tongue, which is mounted at its back end on the said bolt or spindle G, and is provided at its front end with the depending stud or pin I, which is adapted to engage one of the perforations in the tug-strap, and also 40 an aperture, K, in the plate D, as clearly shown in Fig. 2.

The studs F F on the sides of the plate D are engaged in the slots in the sides of the

curved loop, and the said loop is thus allowed considerable play or movement.

50

It will be seen by reference to the drawings, Figs. 1 and 2, that the loop embraces the plate D and the tongue, and bears at its outer end on the latter, and therefore when a strain is put upon the trace (which is attached to the 55 inner or rear end of the loop) the outer or front end of the latter binds down firmly on the tongue, and thus prevents it from becoming accidentally detached. When it is desired to release the tug-strap, draw the curved 60 loop outward until the studs F are near the inner or rear ends of the slots in the arms *c c*, and then swing the outer end of the loop rearward into the position shown in Fig. 3, when the tongue will be free and may be raised to 65 release the tug-strap.

Figs. 4 and 5 show a hook or catch embodying my improvement, the said hook or catch being adapted to be applied to the front end of the tug-strap to engage in a ring on the 70 hames. In the said figures, L represents a hook, which is formed on the front end of the plate D, and on the extremity of this hook (which curves back toward the plate) is mounted the tongue H, which is similar to the 75 tongue shown in the other figures. This hook is engaged in a ring, M, which is attached to the hame of the collar. The curved loop is used in this device, and it is connected to the end of the tug-strap and bears on the tongue 80 in the same way as in the device illustrated in Figs. 1 to 3.

Having described my invention, I claim—

1. The combination of the plate having an aperture, K, and the studs F F on its sides, the 85 tongue H, having the pin or stud to engage the said aperture, and the loop having the slotted arms to receive the studs F F and bear on the tongue, substantially as specified.

2. The combination of the plate D, having 90 the aperture K, and the outwardly-extending ears E E, having a bolt or spindle arranged between them, the tongue H, mounted on the said bolt or spindle and having the stud or pin I, to engage the aperture K, and the loop 95 C, arranged on the plate and adapted to bear

on the tongue, as and for the purpose substantially as specified.

3. The combination of the plate having lateral studs F and an aperture, K, the pivoted tongue H, having a pin or stud, I, to engage the aperture K, and the loop C, having the curved side arms, c c, provided with longitudinal slots mounted on the studs F F, all constructed and arranged substantially as and for to the purpose hereinbefore specified.

In testimony that I claim the foregoing as my own I have hereto affixed my signature in presence of two witnesses.

JESSE THOMAS MERRITT.

Witnesses:

JNO. R. HANCOCK,
I. V. BUNTLEY.
